J. H. POPE

HEEL SEAT ROUGHING MACHINE

Filed Jan. 17, 1920

INVENTOR

Joseph H. Pope
By his Attorney
Nelson W. Throckmorton

UNITED STATES PATENT OFFICE.

JOSEPH H. POPE, OF HAMILTON, MASSACHUSETTS, ASSIGNOR TO UNITED SHOE MACHINERY CORPORATION, OF PATERSON, NEW JERSEY, A CORPORATION OF NEW JERSEY.

HEEL-SEAT-ROUGHING MACHINE.

Application filed January 17, 1920. Serial No. 352,063.

To all whom it may concern:

Be it known that I, JOSEPH H. POPE, a citizen of the United States, and resident of Hamilton, in the county of Essex and State of Massachusetts, have invented certain Improvements in Heel-Seat-Roughing Machines, of which the following description, in connection with the accompanying drawings, is a specification, like reference characters on the drawings indicating like parts in the several figures.

This invention relates to the manufacture of boots and shoes and is illustrated as embodied in a machine especially designed for treating the heel seats of outsoles to facilitate the heel attaching operation.

When cement is employed to hold a heel to the heel seat of an outsole preliminary to securing them together by nails, the heel is liable to slip laterally before the cement sets. This liability is lessened by roughening the sole. When a roughening operation is attempted by a hand-operated tool it is almost impossible to limit the roughening to that portion of the sole which will be covered by the heel, and the same is true when a sole is held in contact with an exposed portion of an ordinary rotary abrader with no means for positively limiting movements of the sole relatively to such abrader.

An object of the present invention is to provide an improved machine for scratching or roughening up a surface of a shoe part such as the tread face of the heel end of a sole over a definitely limited area, as the area of that portion of a sole which is to be covered by the heel of the shoe.

An important feature of the invention comprises the combination with a rotary abrader, of means for determining the proper location of a sole relatively to the abrader, said means definitely prescribing the area and shape of the sole surface to be roughened.

In the exemplification of the invention illustrated in the accompanying drawings the machine comprises a rotary abrader and a rocking gage member substantially tangential to the periphery of the abrader, said gage having a heel-lift shaped opening to define the shape and size of the area of the sole surface to be roughened.

A further feature of the invention comprises a rocking gage of the character referred to having means for preventing it from being rocked beyond a predetermined limit in either direction whereby the action of the abrader will not be extended on to the gage itself beyond the area of the heel seat of the sole.

These and other features of the invention, including certain details of construction and combinations of parts, will be described more fully in connection with the accompanying drawings and pointed out in the appended claims.

Referring to the drawings,

Fig. 1 is a front elevation of a machine embodying my improvements;

Fig. 2 is an elevation looking from the right of Fig. 1;

Fig. 3 is a view looking in the direction of the arrow 3 of Fig. 2, on a larger scale;

Fig. 4 is a detail sectional view showing the means for adjustably mounting the gage;

Fig. 5 is a detail elevation of the means for limiting the rocking movements of the gage; and

Fig. 6 is a plan view of the heel portion of a sole which has been roughened.

The invention is illustrated as applied to a machine of the type illustrated in U. S. Letters Patent No. 1,054,656, granted February 25, 1913, upon an application filed by R. F. McFeely. The machine comprises a frame or standard 12 having bearings for a shaft 13 which carries a pulley 14 upon which is mounted a driving belt, the latter being protected by a casing 15.

Secured to the shaft 13 by suitable means, which may be such as illustrated in the McFeely patent referred to, is an abrader 16, the usual hood being illustrated at 17.

Projecting from the frame or standard 12 is a bearing 18 (Figs. 1 and 4) for a stem or stud 19 having an arm 20 which carries a stud bearing 21 for the end portion 22 of the rocking gage presently described. In order to adjust the pivotal support 19 relatively to the periphery of the abrader, the stem 21 is adapted to be rotated in the bearing 18 and secured in the desired rotative position by a set screw 23.

Preferably a suitable washer 24 will be

interposed between the head of the screw 25 which holds the gage on the pivotal support 21 and the side face of said pivotal support so that the gage as a whole may 5 rock quite freely upon the pivotally support 21.

Extending across the face of the abrader from the end part 22, and preferably integral with said part 22, are two side bars 10 26 to which is secured a plate 27 having an opening approximating the shape of a heel lift. Coacting with the plate 27 are two thin supports 28, and adjustably connected to the side bars 26 are two beveled 15 blocks 29 which are secured in position by screws 30 which pass through slots in the side bars 26, one of said slots being shown at 31 in Fig. 1.

Extending from the end plate 22 of the 20 gage are two lugs 32 in each of which is mounted a stop screw 33 which may be secured in adjusted position by a binding nut 34. The inner ends of the two stop screws 33, as best shown in Fig. 5, are adapted to alternately contact with upper side portions of 25 the arm 20 when the gage as a whole is rocked on the pivotal support 21.

In operation, a sole the heel seat portion 30 of which is to be roughened, is inserted end- wise against the beveled blocks 29 with marginal portions of the heel end of the sole resting upon the plate 27 and the thin supports 28. Said supports 28 are preferably attached to or integral with the blocks 29. 35 By adjusting said blocks along the bars 26 toward the right or left in Fig. 3, the length of the opening in the gage can be varied so that more or less of the length of the area of the sole to be roughened can be pressed into 40 contact with the revolving abrader 16. While the sole is being held by the operator with the margin of the heel seat portion thereof supported by the gage as described, a rocking movement is imparted to the sole 45 and the gage to the limits prescribed by the stop screws 33, thereby shifting the portion of the sole which will be in contact with the abrader from one side to the other of the heel seat portion, the structure being such 50 that it is impossible for any abrading action to be effected upon the marginal portions of the heel seat end of the sole such as shown in Fig. 6 in which the shaded area represents the area of the sole which has been scratched 55 or roughened.

When the stud 19 is secured by the set screw 23 so that the pivotal support 21 is located in the position shown in Fig. 2, the gage will rock on a center practically in line 60 with the periphery of the abrader. By rotatably adjusting said stem 19 the pivot 21 can be set at a greater or less distance from a line which would intersect the periphery of the abrader to accommodate the work 65 being done according to whether heavy or

light roughening action is to be the result of contact with the abrader.

During the use of the machine, the operator merely rocks the shoe slightly about the longitudinal median line of the sole while 70 the sole is in contact with the abrader, the gage serving the purpose of insuring that the sole shall not be rocked so far in either direction as to mar the edge portions of the sole. At the same time, owing to the fact 75 that the sole fits between the side bars 26, while bearing upon the plate 27 and the thin supports 28, said sole can not be shifted from its position in the gage by the operation of the abrader the periphery of which is sweeping across the sole from side to side thereof.

Having described my invention, what I claim as new and desire to secure by Letters Patent of the United States is:

1. A machine for roughening the tread 85 face of the heel end of a sole, having, in combination, a rotary abrader and means for determining the proper location of the sole relatively to the abrader, said means being constructed and arranged to prescribe a 90 definite area and shape of the sole surface to be roughened and being movable to carry all portions of said area into contact with the abrader.

2. A machine of the character described 95 comprising a rotary abrader and a rocking gage member having a rocking axis substantially in line with the periphery of the abrader, said gage having an opening to define the shape and size of the area of the surface to be roughened. 100

3. A machine of the character described comprising a rotary abrader and a rocking gage member substantially tangential to the periphery of the abrader, said gage having 105 an opening to define the shape and size of the area of the surface to be roughened, said gage member having means for preventing it from being rocked beyond a predetermined limit in either direction. 110

4. A machine of the character described comprising, in combination, a rotary abrader, and a work gage pivotally mounted to rock the work for presentation to the abrader on an axis substantially in line with 115 the periphery of the abrader.

5. A machine of the character described comprising, in combination, a rotary abrader, and a plate mounted to rock on an axis substantially in line with the periphery 120 of the abrader, said plate having an opening to permit a portion of the surface of the work held against said plate to contact with the abrader.

6. A machine of the character described 125 having, in combination, a rotary abrader, a work gage mounted to rock the work for presentation to the abrader on an axis lying in a plane which is substantially tangential to the periphery of the abrader, and an ad- 130

justable support for varying the position of the rocking axis of the gage.

7. A machine for roughening the tread face of a sole over a definite area, having, in combination, a rotary abrader, a rocking gage member having an axis about which it is turned to present all portions of said area

of the work to the abrader, said gage member having an opening, and means for varying the size of the opening to vary the treated area of the sole.

In testimony whereof I have signed my name to this specification.

JOSEPH H. POPE.
